UNITED STATES PATENT OFFICE.

JAMES E. SMITH, OF MADISONVILLE, LOUISIANA.

WATCH-HOLDER.

1,257,752.

Specification of Letters Patent. Patented Feb. 26, 1918.

Application filed August 29, 1917. Serial No. 188,876.

To all whom it may concern:

Be it known that I, JAMES E. SMITH, a citizen of the United States, residing at Madisonville, in the parish of St. Tammany and State of Louisiana, have invented new and useful Improvements in Watch-Holders, of which the following is a specification.

The present invention has reference generally to holders and more particularly relates to a watch holder especially adapted for use in conjunction with a belt.

As the primary aim and object, this invention embraces the provision of a device of the above character designed for removable engagement with a belt for holding a watch chain and consequently a watch on the end of the chain from accidental displacement.

It is an equally important object of this invention to provide a device of the above character wherein the construction permits of the ready application of the frame of the holder on a belt as well as the adjustable engagement of the holder with the usual openings in the belt so as to prevent the holder from having accidental sliding movement on the belt.

Among the other aims and objects of this invention may be recited the provision of a device of the character described with a view to compactness, and in which the number of parts are few, the construction simple, the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and where is disclosed for the purpose of illustration a convenient and satisfactory embodiment of the invention. It is to be noted in this connection that minor changes in the construction and arrangement of parts may be made without departing from the principle of operation of the various parts.

The invention is clearly illustrated in the accompanying drawings, in which:—

Figure 1 is a front elevation of the invention applied on the belt of the wearer or user.

Fig. 2 is an enlarged rear elevation of the 55 invention.

Fig. 3 is an enlarged front elevation of the invention.

Fig. 4 is a sectional detail showing the device applied to a belt. 60

Similar characters of reference are employed in all of the above described views, to indicate corresponding parts.

Referring now, more particularly, to the accompanying drawings, there is illustrated 65 a portion of a pair of trousers 1 provided adjacent the upper edge with the usual watch pocket 2 while engageable with the upper edge of the trousers is a supporting belt 3 the outer portion of which is provided 70 with a plurality of uniformly spaced openings 4 for facilitating adjustable engagement with the buckle 5 on the other portion of the belt. Removably and adjustably engaged on the belt is the improved watch 75 holder indicated in its entirety by the numeral 6.

In the present instance the improved watch holder preferably embodies a rectangular loop frame 7 formed of any desirable material such as celluloid, bone or various kinds of metals. This frame is designed for sliding engagement on the belt portion having the openings 4 therein and has one cheek thereof provided with a rectangular opening 8 while a pin 9 projects from the inner surface of the other solid cheek 10 and is designed for engagement with any one of the openings 4 in the belt so as to prevent 85 accidental sliding movement of the frame on the belt. The outer end of the pin as will be understood terminates flush with the plane of the inner surface of the open cheek of the frame.

A projection is formed on the lower end 95 of the frame and is provided with a transverse opening 11 in which is loosely mounted a ring 12 designed for engagement with the link of a watch chain 13, while the watch is adapted to be connected on the other end 100 of the chain and received in the pocket 2.

By this arrangement it is apparent that when the parts have been constructed and applied in the manner described that the watch and chain will be prevented from 105 being accidentally displaced and when the chain 13 is of a shorter length as illustrated the watch is prevented from falling to the

floor or the pavement even should it slip from the pocket. The outer face of the solid cheek 10 of course may be provided with the monogram of the user as indicated 5 in Fig. 3.

It is believed in view of the foregoing description that a further detailed description of the operation of the various parts is entirely unnecessary. Likewise it is thought 10 that the advantages of the invention will be readily apparent.

As many changes could be made in the above construction and many apparently widely different embodiments of this invention 15 could be made without departing from the scope of the invention, it is intended that all matter contained in the above description or shown in the accompanying drawings shall be interpreted as illustrative and not 20 in a limited sense. It is also to be understood that the language used in the following claims is intended to cover all the generic and specific features of the invention herein described and all statements of the 25 scope of the invention which as a matter of language might be said to fall therebetween.

Having thus fully described this invention what is claimed as new and desired to be secured by Letters-Patent is:—

10 1. A watch holder including in combina-

tion with a belt having a plurality of openings in one portion thereof, a rectangular loop frame engageable with the belt and having one cheek thereof open, a pin projecting from the inner surface of the other cheek of the frame for engagement with any one of the openings in the belt, and a ring loosely connected to the frame and adapted for engagement with the watch chain. 35

2. A watch holder of the character described including in combination with a belt having a plurality of openings in one portion thereof, a rectangular loop frame removably engageable with the belt and having one cheek thereof provided with a rectangular opening, a pin projecting centrally from the inner face of the other cheek of the belt and terminating in the plane of the inner surface of the open cheek and designed 40 for engagement with any one of the openings in the belt, a projection formed on the lower end of the frame and provided with a transverse opening, and a ring loosely connected in the transverse opening and adapted for engagement with the watch chain. 45

In testimony whereof I affix my signature.

JAMES E. SMITH.
